UNITED STATES PATENT OFFICE

2,433,270

METHOD OF COATING STITCHED FABRIC

Ida Y. Goldman, Brooklyn, N. Y.

Application April 6, 1944, Serial No. 529,729

1 Claim. (Cl. 117—62)

1

This invention relates to articles which combine certain water absorbing and water resisting characteristics, and has further reference to methods of making such articles.

One object of the invention is to provide a sheeting the component parts of which are interconnected to form a one-piece structure to be sold in the trade as a garment producing fabric, which sheeting has the capacity for the rapid and substantial absorption of liquids to thus increase the comfort of the wearer, combined with the characteristic of arresting the flow of liquids through the sheeting where the absorption capacity thereof should be exceeded or where a time element is required for distribution of the liquid for uniform absorption by the sheeting.

The particular utility of such a sheeting will be instantly apparent by considering its embodiment in a diaper. From the standpoint of the manufacturer of the diaper, he need merely cut the sheeting into blanks and bind the edges to complete the article. From the point of view of the user, the diaper can quickly and fully absorb all liquids, substantially prevent leakage and soiling of bedding and outer garments and avoiding wetting of exposed portions of the body of the child, thus reducing the opportunity for chilling thereof, with resultant colds. Such a diaper, moreover, is highly compact, remains in proper position without slippage of various layers or sheets, and is quick and easy to apply. The waterproofing component is so arranged that it does not prevent complete and rapid absorption of liquids, but arrests the spread thereof, prevents too rapid evaporation with undue cooling of the child's body, and always presents a neat and clean exterior appearance, free of discoloration. It will thus appear that the diaper is soft, warm, and comfortable to the tender skin of a baby.

The manufacturer of the sheeting may cheaply and quickly construct the same by the use of quilting machinery, a water resistant coating being applied by him preferably thereafter.

Another object of the invention is to furnish an improved article of the character described wherein a quilt-like sheeting is provided with an exterior coating of water resistant material that completely closes and seals the openings at the multitude of stitches.

Where cotton batting is used as a filler, it is of considerable advantage to close the stitch openings, especially because the cotton efficiently transmits liquid by capillary action and because the body of the cotton shrinks when it is fully

2

wetted, permitting considerable slackening of the stitches.

Another object of the invention is the provision of an improved quilt-like article having an impregnating coating on a side closing the stitch openings in combination with a very soft, completely-filling batting which provides a backing for the stitch openings to permit the plastic coating material to actually seal the stitch openings instead of only partly closing the same.

Another object of the invention is to provide an improved article of the nature set forth wherein the absorbent side may be relatively coarse for rapid absorption of liquid, and the other side densely woven to require a minimum of coating material and to render the same water proof with only one or two coats, so that the article may be cheap and efficient in a high degree.

A further object of the invention is to provide improved methods of making an article of the character described to assure sealing of the stitch openings without interference by the stitches; to avoid pulling and distortion of the stitches; and to assure uniform coating of the textile at points varying in distance from the stitches.

It has been observed that a plastic for waterproofing a textile must be accurately and uniformly applied on its very first coat, and if small parts are not properly coated, solidification of the first coat may prevent rectification by a subsequent coating, and hence the invention aims to provide the necessary high degree of uniformity.

Other objects and advantages of the invention will become apparent as the specification proceeds.

With the aforesaid objects in view, the invention comprises the novel features, combinations and arrangements of parts hereinafter described in their preferred embodiments, pointed out in the subjoined claim, and illustrated in the annexed drawing, wherein like parts are designated by the same reference characters throughout the several views.

In the drawing:
45 Figure 1 is a fragmentary plan view of a sheeting embodying the invention, with parts removed to show its components.

Fig. 2 is an enlarged sectional view.
Fig. 3 is a fragmentary greatly enlarged view of

50 a portion of the article.
Fig. 4 is a plan view, partly in perspective, showing a garment, such as a diaper, embodying the novel fabric.

Fig. 5 is a diagrammatic view showing a method 55 of practising the invention.

Fig. 6 is a similar view showing modified method.

The advantages of the invention as here outlined are best realized when all of its features and instrumentalities are combined but, useful embodiments may be produced involving less than the whole.

It will be obvious to those skilled in the art to which the invention appertains, that the same may be incorporated in several different constructions. The accompanying drawing, therefore, is submitted merely as showing a preferred exemplification of the invention.

Referring in detail to the drawing, 10 denotes an article such as a sheeting, embodying the invention. The same may include a quilt-like body having opposed sheets of material 11, 12, between which is disposed a batting 13 of intertwined, fibrous, moisture absorbent material, such as a cotton or other vegetable fiber. Interconnecting the sheet members 11 and 12 is a field of stitching coextensive with the article, and including spaced intersecting rows of stitching 14 extending preferably diagonally to the weave of the fabrics 11, 12 for a reason hereinafter described. This stitching passes through the filler 13 and thus affords a unitary structure, and prevents shifting of the filling. The fabric 11 is intended to be a relatively coarse fabric having large interstices through which water can readily pass, and yet sufficiently small to confine the fibers of the padding 13. The fabric 11 may be an open mesh knitted material, but the best results are obtained with the use of a textile whose weave may be approximately 30 by 40. To the contrary, the fabric 12 is preferably densely woven and may have, illustratively, a weave of 60 by 80 so as to be adapted to be rendered waterproof by a minimum application of plastic. Of course the fabrics 11 and 12 may both be alike, in which case the weave may be intermediate of the coarse and dense weaves above mentioned. With conventional cotton batting and ordinary thin textiles, the thickness of the article 10 need not exceed about one-eighth of an inch, but it may be as little as one-sixteenth and as much as three-sixteenths of an inch and realize the objects of the invention. On the outer face of the textile 12 is a coating 15 of water resistant material such as a vinyl resin plastic, this coating having an average thickness preferably not exceeding a few thousandths of an inch. This plastic is impregnated into the textile 12 and into the thread of the stitching 14, and is sufficient to fully close the interstices of the cloth and the holes therein produced by the needle in forming the stitching 14. In fact, the external parts of the stitching thread may adhere to the cloth 12 by reason of the plastic. These results may be accomplished by using approximately one to three ounces of the plastic per square yard of the article 10. For some purposes, an article such as 10 may be made by the use of a precoated fabric 12, but leakage through the stitch holes will occur especially because the batting, if soaked with liquid and then squeezed as by pressure of the wearer's body, will force liquid through the stitch holes.

It is noteworthy that the cotton batting 13 whose fibers are very fine, will closely extend around the threaded portions 16 within the article 10 and hence engage in or at the stitch holes 17 thus affording a backing 18 for the application of the plastic. This backing is increased by the compression of the batting due to the stitching.

This nap-like backing is important because without it, the stitch holes would not be closed unless an exceptional weight of plastic were used. Without a proper backing, the plastic would merely

5 form a rim or lip around the edges of the holes, if a reasonably thin coating is to be used, or a minimum number of applications of the coating. Satisfactory results may be accomplished even if only moderate stitch tension is used. Since the 10 thread becomes united to the coating 15 slippage of the thread is avoided, as where the cotton batting becomes soggy with moisture and loses volume, causing a reduction in stitch tension. Such slippage, if it occurred, would eventually 15 enlarged the stitch holes. By the instant structure, the plastic coating 15 is continuous over the fabric 12 and the stitching 16 affording a fairly smooth and uniform outer surface which will not collect dirt and the like.

20 It will now be seen that the article 10 constitutes a sheeting well adapted to be made by a quilt manufacturer with his existing equipment. Such manufacturer may then apply the coating 15 to complete the article. This article 10 may be sold 25 as a sheeting to be cut and made into garments by ordinary methods. The article has the capacity for absorbing a substantial quantity of liquid at high speed due to the character of the cloth 11 and the cotton 13. The waterproofing coating 15 cooperates to prevent the liquid from striking through and to arrest and deflect the liquid for distribution in the cotton batting. The sheeting 10 is virtually a one-piece structure, whose parts will not shift, and which is capable 30 of being easily sewn and worked to produce garments of substantial strength and durability.

In Fig. 4 is shown an article such as a diaper 20 embodying the novel fabric. Otherwise the same may be of any conventional construction, 40 and is preferably shaped for at least a partial form fit. It may have a body embracing wall 21 made of the sheeting 10. For this purpose, the latter is merely cut to shape and a binding 22 is stitched to its edges to enclose the padding 45 13 and finish the article. Any suitable fastening means may be secured to the article such as tapes or snap fasteners 23. Thus the diaper consists virtually entirely of the sheeting 10 and affords the protection thereof around the body and crotch 50 of the child with proper leg receiving openings at 24. The liquid will be rapidly absorbed and distributed in the filling 13 before it can readily leak out through these openings. The absorbent inner face of the diaper is soft and smooth to the 55 skin of the child. The water resistant outer face will not show soiling or leakage, with the coating 15 resisting wear and preventing rupture of the stitches 14 if the child is sitting on or sliding itself along the floor. The diaper is of a 60 good insulating character for warmth, and prevents excessive evaporation of liquid and consequent chilling of the child's body. It may be readily washed since it fully opens up flat, and is then fairly quick drying. Different color effects 65 may be obtained since the inner cloth 11 may be white while the outer fabric 12 may be pink, or the plastic coating may itself be colored. The appearance is thus very neat, the stitching being partially obscured by a translucent coating as suggested in Fig. 1, but the coating may also be substantially opaque as by using a sufficient color.

The sheeting 10 is susceptible of embodiment in various other articles, such as under-arm shields and in many other relations where excessive perspiration is to be absorbed. It may

be made into head coverings to be used by women who go to bed after washing their hair. These and other instances are intended to be merely illustrative of the advantages obtainable with the invention.

In Fig. 5 is shown an apparatus 25 to illustrate a preferred method of making the article 10, preferably with reference to the provision of the coating 15. Here a sheeting 26 is shown consisting of the article 10 less the coating 15. This sheeting is trained over suitable rollers 27, 28 and is fed along under tension applied by any suitable rollers not shown. Intermediate of the rollers 27, 28 the sheeting 26 is permitted to sag to form a trough as at 29 for receiving coating material in plastic condition as at 30. Acting on this plastic is a doctor blade 31 which is vertically and angularly adjustable. Disposed within in the trough 29 in advance of the doctor blade is a means for working the plastic into the upper face of the sheeting 26 to enter the stitch openings 17 and to penetrate into and around the exposed part of the thread of the stitching 14, and to penetrate the textile 12 to close the pores thereof. The means referred to may include rollers 32, 33 rotating in opposite directions in order to approach the exposed stitch threads from opposite sides to thoroughly work in the plastic in course of a single run or coating operation. In other words the plastic is kneaded into and against the fabric and the stitching, with a shifting and turning of the exposed stitch thread and a forcing of the plastic from different directions before any part of the plastic has had an opportunity to set. A complete adequately penetrative action is assured by succeeding operation of the different kneading rollers 32, 33. The second roller 33 applies the plastic rightward against the direction of the action of the doctor blade, so that there are thus three successive plastic applying actions. The doctor blade performs a final working-in of plastic, smooths the coating and scrapes off excess plastic. The coated product 34 now enters a dryer, not shown, in which the coating is hardened to produce the sheeting 10.

By diagonally disposing the lines of stitching, excessive pull or distortion at the stitch threads is avoided, and yet there is a lateral component of force applying plastic to and at the threads. Hence it is better to position the lines of stitching on the bias than parallel or at right angles to the length of the goods.

By reason of the fine cotton filling 13, as previously described in connection with Fig. 3, a suitable backing 18 at the stitch openings 17 is provided to support the plastic to close and seal these openings. Without this backing, the plastic cover would either break like a bubble, or never deposit except at the edges of the openings. In that sense, the provision of the cotton batting may be regarded as an element of the process or method of coating.

If the first coat is imperfect, it is difficult or impossible to close any openings that may be left by applying succeeding coats. The coating 15 may be applied in one or several coating operations.

The tensions exerted by the different rollers 32, 33 may or may not neutralize each other, but the roller 33 may travel much faster than the roller 32, because roller 33 rotates counter-clockwise.

In Fig. 6 is shown a modified apparatus 35 illustrating a different method embodying the invention. This apparatus includes feed or guide rollers 36, 37 acting on a fabric 26a like that at 26, with a doctor blade 38 at the roller 37, and a kneading means comprising opposed rollers 39, 40 like those at 32, 33. In operation, the method involved is like that for the apparatus 25, with the exception that the doctor blade is applied at a point where the fabric 26a is convexed in order to stretch the fabric 12 more than the fabric 11, this result being aided by the intermediate filling 13. This assures perfect smoothness for the fabric 12 that is being coated, and causes the portions of the stitching 14 that are exposed above the fabric 13 to be stretched taut so that the blade may ride with perfect smoothness and evenness over the stitches and over the adjacent parts of the fabric 12.

With both methods, the stitch holes or large interstices in a very coarse weave are closed by the plastic entering thereinto and actually bonding onto the adjacent cotton padding which serves as a backing for the plastic, this backing being pressed against the holes by the stitching. Thus a difficult problem is overcome, and even garment seams can be waterproofed at the stitches by disposing a thin line of soft cotton batting within the seams and then stitching along that line to construct the seam, and finally coating.

It is thus seen that there are provided new articles of manufacture and improved methods of making the same to realize all the various objects and advantages of the inventions disclosed.

35 I claim:

The method of coating a stitched fabric so as to impregnate the latter and close the holes formed by the stitching, including applying plastic coating material to the fabric at one side thereof, kneading the plastic material into the fabric by moving the plastic first in one direction then in a different direction at an angle to the direction of the stitches, and then scraping the fabric to remove excess of plastic material, the kneading and scraping being performed in a single coating operation and before the plastic that is being worked has had an opportunity to harden.

IDA Y. GOLDMAN.
